Primary Examiner — Derrick Holland*Assistant Examiner* — Jennifer O King(74) *Attorney, Agent, or Firm* — Michael A. Kerr; Kerr IP Group, LLC**CLAIM**

I claim the ornamental design for a single cable guide for securing a cable, as shown and described.

DESCRIPTION

FIG. 1 is an isometric view of a single cable guide for securing a cable, showing my new design;

FIG. 2 is a front elevation view thereof;

FIG. 3 is a right elevation view (at 90° from the front view) thereof;

FIG. 4 is a bottom plan view thereof;

FIG. 5 is a isometric view thereof, shown in environmental use;

FIG. 6 is a front elevation view thereof, shown in environmental use;

FIG. 7 is a right elevation view (at 90° from the front view) thereof, shown in environmental use; and,

FIG. 8 is a bottom plan view thereof, shown in environmental use.

The broken lines shown represent unclaimed subject matter and form no part of the claimed design.
